VESPER ANDERSON SCHLENKER, OF ORANGE, NEW JERSEY

ACOUSTIC DIAPHRAGM

Application filed March 16, 1928. Serial No. 262,290.

This invention relates to sound reproducing apparatus and more particularly to a diaphragm for converting mechanical vibrations into sound, and has particular application in loud speakers utilized for converting electrical waves or oscillations into sound waves corresponding thereto.

In the past it has been customary to utilize some form of electrical vibrating device such as an electro-magnetic or electro-dynamic motor for vibrating direct acting diaphragms. It has been realized that the sound waves produced by such arrangements are by no means faithful reproduction of the electrical waves supplied to the driving motor, since distortion is introduced to a greater or less extent. A portion of such distortions may occur in the motor element itself, particularly when it is of the so-called "electro-magnetic" type, in which a vibrating armature, spring biased to one position, is utilized.

In addition, distortion also occurs in the diaphragm itself, and while the causes of distortion in the motor elements are, to a certain extent known, in my opinion, prior to the present invention, very little has been known about the distortion produced by the diaphragm itself.

It is an object of this invention to provide a diaphragm which is in itself capable of giving an extremely faithful reproduction of the vibrations impressed thereon: that is to say, a diaphragm which will deliver to the air an extremely faithful copy in the form of sound waves of the mechanical vibrations impressed upon it.

It is a further object of this invention to provide an acoustic diaphragm in which the distortions heretofore present in diaphragms are eliminated or substantially reduced.

It is a further object of this invention to provide a self-supporting metallic diaphragm of sufficient size to operate directly upon free air, having a mass which is negligible or small in comparison with air loading thereon at sound frequencies less than 1000 cycles.

It is a further object of this invention to provide a self-supporting diaphragm, substantially devoid of inherent damping and

inherent stiffness and structurally stiffened by being formed in a manner which distributes the structural stiffness throughout the diaphragm in a particular way, to be hereafter described.

It is a further object of this invention to provide a self-supporting direct-acting diaphragm having very low inherent damping and inherent stiffness, and having a propagation constant which is substantially independent of frequency and approaches the propagation constant of free air.

Still other objects and advantages of my invention will be apparent from the specification.

The features of novelty which I believe to be characteristic of my invention are set forth with particularity in the appended claims. My invention itself, however, both as to its fundamental principles and as to its particular applications will best be understood by reference to the specification and accompanying drawing, in which:

Figure 1 is a perspective view of a surface having the form of a hyperbolic paraboloid.

Figure 2 is a sectional view of a diaphragm generated by the revolution of a curve having the equation $Y = \text{Log}_e mx$.

Figure 3 is a graph showing the generating curve: and,

Figure 4 is a side elevation partly in section showing one form of a loud speaker according to my invention.

In the usual form of direct-acting or so-called "sounding-board" loud speakers, it is usual to impress the mechanical vibrations which are to be converted into sound, upon the diaphragm or vibrating surface at substantially a single point, or at any rate, at an extremely small part of the area of the diaphragm. The mechanical vibrations so impressed, travel to all parts of the diaphragm and the vibrations of the various elements of the diaphragm set into vibration the air adjacent thereto.

It is known that extremely complex vibrations, corresponding to speech or music may be resolved into a number of sinusoidal vibrations of different frequencies and amplitudes, the resultant of which corresponds to the par-

ticular speech or music wave. The diaphragm may thus be regarded with respect to the transmission of vibrations from the point of application to other parts thereof, as a mechanical power transmission line, which is subjected to sinusoidal vibrations of various frequencies and amplitudes, and which vibrations must be transmitted through the diaphragm. Of course, it will be understood that as the vibrations travel through the diaphragm a portion of their energy is transferred to the atmosphere surrounding the diaphragm. This transfer of energy I term the "radiation" of the diaphragm.

The nature of the distortions which occur in such diaphragms may be more easily understood, it is believed, by considering the analogous case of a telephone transmission line. As is understood, the telephone line itself has definite characteristics, such as inductance, capacity, resistance, leakage, and attenuation, the attenuation being a function of the other constants of the line, and also of frequency. In the case of a telephone line, it is naturally desired to keep the leakage as low as possible; in other words, to deliver as high a percentage of the input power at the output end as is possible. In this respect, the functioning of an acoustic diaphragm does not correspond with a power transmission line, since in an acoustic diaphragm, it is desired to make the radiation, which may be said to correspond to the leakage of a telephone line, as high as possible.

Considering the distortion which is introduced after the vibrations are impressed upon the diaphragm, it may be stated that in general they fall within two classes: (1) distortion which may arise within the diaphragm itself, due to various causes, which will be discussed later: and (2) distortion and loss of efficiency which may take place in the radiation from the diaphragm to the atmosphere, in a manner which will hereinafter be described more in detail. The first of these effects, namely the distortion within the diaphragm itself, arises because the flexural waves set up in the material of the diaphragm travel at a speed which, to a certain extent, varies with the frequency of the impressed wave, and because the attenuation varies with the frequency; such distortions are, in general, analogous to the distortion occurring in the transmissions of telephone currents along a telephone line, wherein the waves travel at a speed which is equal to

$$\frac{2\pi p}{\beta}$$

where "p" represents frequency, and β is a function of the constants of the line, and the frequency, called the wave length constant.

The amplitude of currents travelling along such a line is decreased in the ratio of $1:e^{-a}$ per mile of transmission line, where "a" is

the attenuation constant, which in turn is a function of the primary constants of the line, and of frequency.

The effect of this is that as the voice currents travel along such a line, the currents of various frequency are dephased to a greater or less extent, depending upon the constants and length of the line and frequency, and are also changed in their relative amplitudes, the higher frequencies being attenuated to a greater extent than the lower frequencies. This distortion, if permitted, will ultimately render speech completely unintelligible.

Unless prevented by means such as I contemplate, a similar effect will take place as the complex vibrations impressed at one point on an acoustic diaphragm travel to the other points of the diaphragm: in the case where the velocity of propagation of the flexural vibrations is different at different frequencies, phase distortion will occur, as will be readily understood, and amplitude distortion will occur in case the inherent damping or energy loss in the diaphragm is different for different frequencies, so that if a complex vibration be impressed at one point on the diaphragm, the vibration of another point at a distance from the first point, will not be truly similar to the vibration of the first point. Under such conditions, naturally the vibrations impressed upon the air will differ at different points of the diaphragm, and the difference or distortion will, in general, be greater the larger the size of the diaphragm, and the greater the difference in velocity of wave propagation and attenuation with frequency. This distortion is particularly noticeable in the case of diaphragms of non-metallic material, such as paper cones and fabric diaphragms, and becomes increasingly objectionable as the size of the diaphragm is increased. It is evidenced by a "muffled" tone, poor articulation, suppression of the higher frequencies and a general lack of clarity and tonal definition, giving speech an unnatural quality.

In order to minimize this distortion, it is advisable to arrange the diaphragm in such a way that waves of all frequencies travel at the same speed in the material of the diaphragm, and further, that all frequencies attenuate in the same ratio. However, while such an arrangement would eliminate the distortion within the diaphragm itself and in its radiation, it would not necessarily eliminate a part of the second undesired effect, namely, loss of efficiency in radiation from the diaphragm. This second effect may be characterized as due, in general, to the speed of travel of flexural waves in the diaphragm being different from the speed of travel of sound in the air. An example, it is believed, will serve to clarify this point. If a push be impressed at one point in the diaphragm, a displacement of

the diaphragm occurs at that point and a corresponding compression of the air at that point occurs on one side of the diaphragm. This compression travels outwardly in the form of a constantly expanding hemisphere of compression followed by rarefaction, which travels across the diaphragm at the speed of sound in air. Now, it will be apparent that if the flexural waves in the diaphragm travel at the same speed, the original sound wave in air will be continuously absorbing energy from the diaphragm at the proper point on the wave front: however, if the speed of travel of flexural waves in the material is greater or less than the speed of sound in air, the sound wave in air running across the face of the diaphragm will be displaced with respect to the corresponding flexural wave travelling in the material of the diaphragm itself, and energy will be supplied from the diaphragm to the air with an improper phase relation, which will cause reinforcement of the sound waves in the air at certain points on the diaphragm and partial neutralization at other points. The result of this is that as the ratio of velocity of propagation of sound in air to that of flexural waves in the material of the diaphragm varies from unity, the radiation drops, while the losses remain the same, or, in other words, the proportion of energy converted into sound waves decreases. Moreover, if the velocity of propagation of flexural waves in the diaphragm varies with the frequency, the radiation will be different for different frequencies, being least efficient on frequencies at which the velocity of flexural variations differs most widely from that of the velocity of sound in air. This will cause partial suppression of such frequencies. For these reasons, it is desirable not only to arrange the diaphragm so that flexural waves of all frequencies travel at the same speed and attenuation at the same rate, but also so that the velocity of propagation of flexural waves in the material should equal as closely as possible that of sound waves in air. If this is done, the distortions occurring after the vibrations are impressed upon the diaphragm are eliminated or minimized, and if the diaphragm be operated by a driving motor which is substantially free of distortion, an extremely pure reproduction of sound will be obtained.

55 The general condition for distortionless transmission in a telephone line is $CR=LS$, where "C" represents capacity: "R", resistance: "L," inductance: and "S", leakage per unit of line length. Under this condition, currents of all frequency travel at the same speed and attenuate at the same rate. In general, the same is true for an acoustic diaphragm, but in this instance, the proper physical constants must be used: capacity corresponds to stiffness: resistance to inher-

ent damping of the material itself, such as occurs if the diaphragm be operated in a vacuum: inductance to mass: and leakage to radiation.

It is essential that the diaphragm be critically damped in order to prevent any tendency to resonance of the diaphragm as a whole or in parts, and in order to prevent transient vibrations. This critical damping is obtained by utilizing material having minimum surface density, and by arranging the diaphragm so that it has a high radiation resistance by virtue of close coupling to the air.

Because of minimum surface density required, the material will be so thin as to have very low inherent stiffness, and in order to obtain high radiation and a velocity of wave propagation approaching that of sound in air, stiffness must be imparted to the diaphragm by structural formation. While a high degree of stiffness can be obtained by increasing the thickness of the diaphragm, and while this is the normal way of increasing the stiffness of a diaphragm, it is undesirable in the present instance, and this is accomplished by forming the diaphragm in a special shape, which I find to be particularly adapted to the purpose.

The diaphragm, according to my invention, is preferably formed of metal having the least possible mass, such as aluminum alloys, and is formed from sheets so thin as to have very low inherent stiffness. The material is given what I term "structural stiffness" by forming the diaphragm in such a manner that it has reversed curvature at every point within its periphery: that is to say, if two planes at right angles to each other be passed through the diaphragm, the intersection between the diaphragm and one plane will be curved continuously in one direction, and the intersection between the other plane and the diaphragm will be curved continuously in the opposite direction. This particular curvature is given the diaphragm so that for any deformation normal to the diaphragm at any point, compression will be set up along the line of one curvature, and tension will be set up along the line of the other curvature, and if the direction of deformation be reversed, the compression and tension components will be reversed, that curvature which was formerly under tension being under compression and vice versa; the result of this is the formation of a "dynamically stable" surface which minimizes the tendency to blasting or extraneous noises produced by the diaphragm itself. An example of such a surface is the hyperbolic paraboloid, or saddle shaped surface, well known to mathematicians. I believe that the blasting, which may take place at any point on paper cones, is an indication of the presence of dynamic instability, and is evidenced when a surface suddenly shifts from one form to another. For example, consider

a small disc of metal which is dished in one direction so as to have a slight curvature. It will be understood that there are present certain strains in the material which tend to make it hold such a dished shape. If now, 5 the disc be pressed in such a manner as to cause it to dish in the opposite direction, it will resist deformation up to a certain point, and then will suddenly swing over to the other condition in which the dishing is reversed, 10 producing a sudden snap. An analogous condition I believe to exist in the well known paper cones. Any elementary area of such a cone is dynamically unsymmetrical and unstable, since the forces which come into play 15 for an inward deformation at any point on the cone are different from those which come into play for an outward deformation thereof. If a stress resulting from deformation be resolved into radial and circular components, it 20 will be seen that for an inward deformation at any point on a cone, tension is produced radially and compression circumferentially, whereas for an outward deformation of the same point, tension is still produced radially 25 and tension is also produced circumferentially.

In the diaphragm according to my invention, there is always dynamic stability, in 30 that the deformation at any point produces compression in one component and tension in the other component which oppose each other: if the direction of deformation be reversed, the component stresses will be reversed, so that any point on the diaphragm 35 according to my invention, is what I term "dynamically stable", since tension in one component is always opposed by compression in another component.

I prefer to form the diaphragm according 40 to my invention of material having the least possible mass and damping within itself, and for this reason I utilize metal, preferably aluminum alloys, having minimum mass and relatively high strength. In order to maintain the mass at the lowest possible amount, 45 and thereby permit maximum radiation, I utilize metal of the greatest possible thinness, preferably not more than a few thousandths thick. Satisfactory results have been obtained by the use of such alloy 0.002" thick 50 and having a mass not exceeding 0.03 grams per square centimeter. From a purely theoretical standpoint, it might be desirable under certain conditions to use even thinner 55 material but practical difficulties of working extremely thin material will usually be too great to obtain uniformly satisfactory results.

60 The diaphragm may be conveniently made in the form of a surface of revolution, such as the logarithmic surface of Figure 2. In this instance, the surface may be considered as being generated by the rotation of a curve represented by $Y = \log. mx$, about an axis

65 $R-R$, which does not intersect the curve within the generating segment. The surface so produced will thus be seen to have the general shape of an exponential horn. The diaphragm is preferably provided with a 70 domed portion at its center which is reverse- 75 ly curved, and the constants of the generating curve, the axis of revolution, and the segment used, of the diaphragm are so chosen 80 that the slope of the diaphragm adjacent the domed portion, or in other words the angle α 85 between the inner edge of the diaphragm and the α axis (Figure 2), is approximately 50° , whereas the angle γ between the outer portion or edge of the diaphragm and the α axis, 90 is about 10° to 15° . The constants are like- 95 wise so chosen that the maximum curvature in the radial direction occurs adjacent the outer edge of the diaphragm, as at point C. It will be noted that under these conditions, 100 the radial curvature is greatest where the circumferential curvature is smallest and vice versa. In other words, if the radial curvature be designated as C_r and the circumferential curvature or curvature normal to the radial curvature, be designated as C_n , 105 then it will, in general be true that

$$C_r \times C_n = -K.$$

110 It should be pointed out that it is not necessary that this condition be fulfilled exactly, but, satisfactory results are obtained when it is approached. For example, the curvatures may vary in such a manner that K may change in the ratio of five to one, without particularly noticeable loss of quality and efficiency, but a change in the ratio of one thousand to one would be quite noticeable.

115 Other curves in addition to those already described, may be utilized in the formation 105 of the diaphragm. For example, the radial curvature may be in the form of a cycloid or a parabola, but in any case if the surface is 120 one of revolution, it is desirable to have the greatest radial curvature adjacent the outer periphery of the diaphragm, since at that point the circumferential curvature is smallest.

125 Referring now more particularly to Figure 1, I have shown a surface in the form of a hyperbolic paraboloid which is a so-called 115 ruled surface rather than a surface of revolution, from which it will be evident that any elemental area within the periphery of the diaphragm is reversely curved, the curvature along one plane being convex, and the curvature along another plane at right angles thereto being concave.

130 Referring now more particularly to Figure 2, in which I have shown a section of a 125 diaphragm comprising a surface of revolution: OY designates the axis of the diaphragm and OX the axis normal thereto. The constants and segment of the curve and the axis of revolution $R-R$ are so chosen

and the size of the diaphragm is so chosen with respect to the constants of the curve, that the angle α is approximately 50° , whereas the angle γ is from 10° to 15° . The limits of the generating curve are so placed that the point of maximum curvature, such as C, lies adjacent the outer periphery p of the diaphragm.

The driving force is preferably applied around the circle generated by the point D, as the generating curve is revolved about the axis R—R.

Referring now more particularly to Figure 3, I have shown the generating curve whose equation is $Y = \log_e mx$, the curve following the points 1, 2 and 3. It will be noted that the curve crosses the x axis at a point where x is equal to unity.

Referring now more particularly to Figure 4, 5 designates a diaphragm such as shown in Figure 2, and 6 is a hollow frustroconical member suitably attached to the apex of the diaphragm, as by cementing, and 7 is a driving rod secured to the hollow frustroconical member 6, as by nuts (not shown) or in any other suitable manner: 8 designates a driving motor of any suitable type, such for example as a balanced armature motor. It will be understood, however, that any other type of driving motor may be utilized, as for example, the so-called "dynamic" type of drive. The form of drive forms per se no part of the invention claimed herein, and is therefore not shown in detail.

While the actual size of the diaphragm is not of great importance, it will be understood that the distortions, which it is the object of this invention to overcome, are more noticeable in the prior art diaphragms as the size is increased. If the diaphragm according to my invention is of sufficient size so as not to render desirable the use of a baffle plate, it may be operated in free air supported as its center and with its periphery entirely free. If, however, the size of the diaphragm is decreased to such an extent that there is an appreciable loss of low frequencies when the diaphragm is so operated, it is preferable to provide some form of baffle arrangement, such as that shown in the drawing wherein 9 designates diagrammatically a suitable form of baffle provided with an opening therein and having its inner edge 10 reversely bent. For the purpose of providing an air seal between the baffle plate 9 and the diaphragm, a ring or annulus of flexible material 11, such as plush, linen, leather or the like, may be cemented to the periphery of the diaphragm and secured against the flange 10 by suitable tension members, such as several turns of string 12. This particular construction forms per se no part of my invention.

While I have shown and described certain preferred embodiments of my invention, it is

understood that modifications and changes may be made without departing from the spirit and scope of my invention, as will be understood by those skilled in the art, and also while I have described the use of my invention in a loud speaker for converting mechanical vibrations into sound, it is apparent that it may equally well be utilized as a microphone diaphragm for the purpose of converting sound waves into mechanical motion, or electrical currents corresponding thereto.

I claim:

1. A sound reproducer comprising a self-supporting, direct acting diaphragm of thin metal, of such shape that any section containing the axis is a curve convex toward the said axis and any section made by a plane normal to the axis is a curve concave toward the axis, the mass and area of said diaphragm being such that the fundamental period thereof when vibrating freely as a bell is below the lowest important voice frequency.

2. A sound reproducer comprising a self-supporting, direct acting diaphragm of relatively thin metal in the form of a surface so formed that deformation of any point within the periphery of said diaphragm in a direction normal to the surface at said point produces tension in one component and compression in a component normal thereto, and deformation of said point in the opposite direction produces reversed stresses.

3. A sound reproducer comprising a self-supporting, direct acting metallic diaphragm having minimum inherent stiffness, relatively high structural stiffness, and having a mass not substantially exceeding 0.03 grams per square centimeter, and so formed that the surface thereof has positive and negative curvature in planes at right angles to each other.

4. A sound reproducer comprising a self-supporting, direct acting curved metallic diaphragm, the mass of said diaphragm being small in comparison with air loading thereon at sound frequencies up to 1000 cycles, said diaphragm having relatively small inherent stiffness and relatively high structural stiffness, and being so formed that the curvatures at right angles are opposite in sign.

5. A sound reproducer comprising a self-supporting, direct acting metallic diaphragm having a mass which is small in comparison with air loading thereon at sound frequencies up to 1000 cycles, and having relatively high structural stiffness and having a negative curvature in one component and a positive curvature in the component at right angles thereto, the curvatures being such that the product of curvatures at any point on said diaphragm is substantially constant.

6. A sound reproducer comprising a self-supporting, direct acting metallic diaphragm

having a mass which is small in comparison with air loading thereon at sound frequencies up to 1000 cycles, and having low inherent stiffness and high structural stiffness, in the form of a surface of revolution convex toward the axis and having its greatest radial curvature adjacent the outer periphery.

7. A self-supporting, direct acting metallic diaphragm, the mass of which is small in comparison with air loading thereon at sound frequencies less than 1000 cycles, having low inherent stiffness and reversed curvature at any point, and having an attenuation constant which is substantially independent of frequency.

15 8. A self-supporting, direct acting metallic diaphragm, the mass of which is small in comparison with air loading thereon at sound frequencies less than 1000 cycles, having low inherent stiffness and reversed curvature at any point, and having a velocity of propagation of flexural waves which is substantially independent of frequency.

9. A self-supporting, direct acting metallic diaphragm, the mass of which is small in comparison with air loading thereon at sound frequencies less than 1000 cycles, having low inherent stiffness and reversed curvature at any point, having an attenuation constant which is substantially independent of frequency, and having a velocity of propagation of flexural waves which is substantially independent of frequency.

10. The method of minimizing distortion in a direct acting acoustic diaphragm which comprises forming said diaphragm of metal so thin as to have very low inherent stiffness, and stiffening said diaphragm by forming the material thereof into a surface having reversed curvature in directions at right angles to each other.

35 11. The method of minimizing distortion in a direct acting acoustic diaphragm, which comprises forming said diaphragm of metal so thin as to have very low inherent stiffness, and stiffening said diaphragm by forming the material thereof into a surface having reversed curvature in directions at right angles to each other in such manner that the 45 product of curvatures at every point within the periphery of said diaphragm is substantially constant.

12. An acoustic diaphragm having the shape of a surface of revolution formed by 55 revolution of a line having a continuously changing radius of curvature, the portion of the line having the least radius of curvature generating the portion of the diaphragm surface adjacent the outer periphery thereof.

60 13. An acoustic diaphragm having the shape of a surface of revolution formed by revolution of a logarithmic curve.

14. An acoustic diaphragm having the shape of a surface of revolution formed by 65 revolution of a logarithmic curve, the por-

tion of the curve generating the outer peripheral portion of the diaphragm having a less radius of curvature than the portion of the curve generating the portion of the diaphragm toward the center thereof.

Signed at New York city, in the county of New York and State of New York, this tenth day of March, A. D. 1928.
